(57) **CLAIM**

We claim the ornamental design for a lid for beverage container, as shown and described.

DESCRIPTION

FIG. 1 is a perspective view of a lid for a beverage container according to the new design;

FIG. 2 is a front view of the lid for a beverage container shown in FIG. 1;

FIG. 3 is a side view of the lid for a beverage container shown in FIG. 1;

FIG. 4 is a back view of the lid for a beverage container shown in FIG. 1;

FIG. 5 is a top view of the lid for a beverage container shown in FIG. 1; and,

FIG. 6 is a bottom view of the lid for a beverage container shown in FIG. 1.

The broken lines shown in the drawings are included for the purpose of illustrating environmental structure and form no part of the claimed design.

1 Claim, 5 Drawing Sheets
